UNITED STATES PATENT OFFICE.

FRANK J. CHAT, OF CHICAGO, ILLINOIS, ASSIGNOR TO HARRY R. GIBBONS, OF CHICAGO, ILLINOIS.

BED-ELEVATING DEVICE.

1,378,096.

Specification of Letters Patent. Patented May 17, 1921.

Application filed November 17, 1919. Serial No. 338,666.

To all whom it may concern:

Be it known that I, FRANK J. CHAT, a citizen of the United States, and a resident of the city of Chicago, county of Cook, and 5 State of Illinois, have invented certain new and useful Improvements in a Bed-Elevating Device, of which the following is a specification.

My invention relates to a new and useful 10 improvement in a bed elevating device and has for its object the provision of a simple, easily operated, substantial, and efficient device of this class.

Another object is the provision of a bed 15 elevating device capable of being quickly applied to a bed.

Other objects will appear hereinafter.

The invention consists in the combinations and arrangements of parts hereinafter 20 described and claimed.

The invention will be best understood by reference to the accompanying drawings forming a part of this specification, and in which,

25 Figure 1 is a front elevational view of my invention applied to a bed.

Fig. 2 is a side elevational view of my device applied to a bed with parts in section.

30 Fig. 3 is a longitudinal sectional view taken on line 3—3 of Fig. 2.

The approved form of construction of my invention which is adapted to be used in connection with a bed 4, attached to the legs 35 or posts 5 of the bed, consists of a frame having longitudinally extending members 6 and 6', spaced apart as shown. The members 6 and 6' are connected at each of their adjacent ends by suitable upright members

40 7 and 7'. Projecting outwardly from the lower ends of each of the members 7 and 7' are suitable shoes 8 and 8' each of said members 8 and 8' having a vertically extending threaded opening 9 for the reception of a

45 threaded shaft 10. The lower end of the shaft 10 is rotatively mounted in a collar 11 which projects upwardly from a base 12. The upper end of the shaft 10 engages in a suitable bearing 13 which projects down-

50 wardly from the housing 14, the housing 14 being shown in the drawings with the front wall removed. Securely mounted to the extreme upper end of the shaft 10, within the housing 14 is a bevel gear 15, which is adapt-

55 ed to mesh with a bevel gear 16 mounted

within the housing 14, fixedly upon a shaft 17 which projects through the lateral wall of the housing 14. Projecting upwardly from the base 12 are suitable guide members 18 which serve as a guide for the members 8 60 and 8' when the same are moved upwardly or downwardly. As shown, the shaft 17 projects through the outer wall of one of the housings 14 and to this end of the shaft which projects beyond this outer wall is 65 fixedly mounted a suitable crank 19 for the purpose of rotating the member 17.

The upright members 7 and 7' which carry the members 8 and 8' are adapted to be securely fastened to the opposite legs or posts 70 5 of the bed with which the device is intended to be used. In securing the members 7 and 7' to the posts or legs of the bed with which used I have provided suitable clamping members 20 and 21. These members 75 when co-acting form a sleeve which embraces the legs or posts of the bed and also the members 7 and 7'. Suitable bolts 22 are provided for the purpose of bringing the members 20 and 21 into close engagement 80 with each other thereby binding the members 7 and 7' in rigid and unmovable connection with the legs or posts of the bed.

In operation the device is attached to the legs or posts of the bed with the base members 12 resting upon the floor. Upon the turning of the crank 19 the bevel gears will cause a rotation of the members 7 and 7'. This rotation of the members 7 and 7' will cause either a lowering or an elevating of the 90 members 8 and 8'. This will result in consequence of the members 7 and 7' being rigidly connected to the posts or legs of the bed, in a lowering or elevating of the end of the bed to which attached. 95

This device is particularly useful in hospitals where it is sometimes required to have the head of the bed higher than the foot of the bed or vice versa.

While I have illustrated and described the 100 preferred form of construction for carrying my invention into effect, this is capable of variation and modification without departing from the spirit of the invention. I, therefore, do not wish to be limited to the 105 precise details of the construction set forth, but desire to avail myself of such variations and modifications as come within the scope of the appended claims.

Having described my invention, what I 110

claim as new and desire to secure by Letters Patent is:—

1. In a device of the class described, a frame adapted to be attached to a bed; threaded upright members rotatively mounted in bearings secured to said frame, and adapted upon rotation, to adjust the elevation of said bed; a base for pivotally supporting each upright member and means 10 of rotating said upright members, substantially as described.
2. In a device of the class described, a frame adapted to be attached to a bed; threaded upright members rotatively mounted in bearings secured to said frame; bases for pivotally supporting said upright members; gear wheels mounted on the upper end of said members; a horizontally disposed shaft; gear wheels mounted on said shaft 15 adjacent the ends thereof and meshing with said first mentioned gear wheels; and means for actuating said shaft, substantially as described.
3. In a device of the class described, a frame; means of attaching said frame to bed posts; bearing shoes secured to opposite sides of said frame at the lower end thereof; threaded upright members rotatively mounted in said bearing shoes; means of adjusting the relative position of said bearing shoes on said upright members; a supporting base for each upright member; and 20
- 30

means of actuating said last mentioned means, substantially as described.

4. In a device of the class described, a frame; clamping sleeves for attaching said frame to bed posts each sleeve containing a plurality of fastening means; bearing shoes secured to opposite sides of said frame at the lower end thereof; threaded upright members rotatively mounted in said bearing shoes; means of adjusting the relative position of said bearing shoes on said upright members; and means of actuating said last mentioned means, substantially as described. 45

5. In a device of the class described, a frame; clamping sleeves for attaching said frame to bed posts; vertically movable bearings secured to opposite sides of said frame, at the lower end thereof; threaded members 50 rotatively mounted in said bearings; bases containing sockets for pivotally supporting said threaded members; and means for actuating said threaded members to lower or elevate said frame and bedposts. 55

In testimony whereof I have signed my name to this specification in the presence of two subscribing witnesses.

FRANK J. CHAT.
